HEAT EXCHANGER

Fred M. Young, Racine, Wis.

Application May 17, 1939, Serial No. 274,099

2 Claims. (Cl. 257—259)

The present invention relates to radiators used for cooling internal combustion engines particularly large Diesel engines and the like wherein the radiator is a separate self contained unit having a fan and a coolant circulating pump mounted thereon and receiving power for driving the fan and pump either from the engine by means of V-belts or direct from an electric motor or otherwise.

The principal object of the present invention is to provide a device which may be manufactured, sold and shipped as a complete unit which is simple, compact and economically operated.

An object of the present invention is to provide vertically positioned finned headers and horizontally positioned tubes whereby the bottom ends of the headers may be slidably secured to the frame members to thereby provide means for unequal expansion and contraction of the tubes and frame.

Another object of my invention is to provide means in the headers whereby the coolant may move through certain groups of tubes in series.

A still further object of the present invention is to provide a structure which may be moved about on its base and suitably secured to almost any kind of foundation and wherein the device will operate more satisfactory than if made a part of the engine installation.

To these and other useful ends my invention consists of parts, combinations of parts, or their equivalents, and mode of operation, as herein-after set forth and claimed and shown in the accompanying drawings in which:

Fig. 1 is a front elevational view of my complete unit as viewed from the fan and pump side.

Fig. 2 is a side elevational view of the design illustrated in Figure 1.

Fig. 3 is a fractional view taken on line 3—3 of Figure 2.

Fig. 4 is a fractional section taken on line 4—4 of Figure 2.

Fig. 5 is a front elevation of the core assembly taken on line 5—5 of Figure 2.

Fig. 6 is a top view of the frame brace which carries the circulating pump.

Fig. 7 is a section of the frame brace taken on line 7—7 of Figure 6.

Fig. 8 is a fractional sectional view taken on line 8—8 of Figure 1.

As thus illustrated, my invention consists of two side base members 10—10 and being secured together at one end of the assembly preferably by means of an inverted U-shaped channel 11 which also acts as supporting means for the cir-

culating pump as will hereinafter appear. Member 11 has secured to its ends plates 12—12 as illustrated in Figures 6 and 7 having openings 13 by means of which they may be securely attached to members 10 in the position illustrated in Figures 1 and 2. The rear ends of frame members 10 are secured together by means of an inverted U-shaped bracket 14, the ends of which are preferably welded to members 10 thus members 11 and 14 act to securely hold members 10 in spaced relation and form a rigid supporting frame upon which to mount the other members of the unit.

The present invention differs somewhat from conventional cooling units in that the coolant tubes are horizontally positioned between vertically positioned headers 20 and 21. Tube plates 22 are suitably secured to the inner open faces of the headers by means of suitable gaskets and spaced bolts. The tube plates are operatively connected together by means of circulating tubes 23, these tubes being preferably flattened with their flat sides positioned horizontally as illustrated in Figure 8.

I provide a multiplicity of closely spaced fins 24 through which the tubes extend thus a suitable operating connection is made between the two headers, header 20 being provided with an inlet connection 25 and header 21 with an outlet connection 26.

30 I preferably provide partitions 27 and 28 in headers 20 and 21 as illustrated in Figure 5. Thus it will be seen that the coolant may enter at 25, pass into header 21 and return from this header into header 20 through certain tubes and then return from header 20 to the portion of header 21 which is below partition 28. Thus I provide what I term a 3 pass radiator or heat exchanger. That is, the tubes are divided into three sections through which the coolant passes in series. Clearly other arrangements of partitions may be provided with which to make a 2 or 4 pass core.

35 Headers 20 and 21 are secured to frame member 10 as follows (see Figure 4): So far as members 20 and 21 are concerned, they are externally duplicates except member 20 is positioned with the inlet at the top and 21 is positioned so the same opening acts as an outlet at the bottom. In other words, the headers are turned end for end.

The ends of each header are made flat, the bottoms being provided with studs 29 which extend through enlarged openings 30 in the top flange of each of the frame members. A sleeve 31 having a rubber bushing 32 is concentrically

positioned below opening 30 and is welded to the flange of members 10 as illustrated. Bushing 32 is preferably made of rubber and is provided with an aperture suitable for the reception of bolt 29 and being slightly longer than sleeve 31.

I provide a washer 33 and nuts 34 and 35 whereby the washer may be held snugly against bushing 32 but not in contact with sleeve 31 tight enough to prevent end movement of the washer. Nut 35 acts as a lock for nuts 34. Thus it will be seen that members 10 are definitely spaced and that the headers are definitely held in position on these members but that they may move because of opening 30 and rubber bushing 32.

Clearly tubes 23 of the core will be free to expand and contract. At the same time, the core assembly will be firmly held to the frame members.

I provide vertical frame plates 40 having in-turned edges 41 (see Figure 3), the plate ends being secured to frame members 10 in any suitable manner. These plates are preferably secured to the headers by means of intermediate plates 42. These plates are secured to the headers as illustrated in Figures 2 and 3 and to plates 40 by means of rubber washers 43 and bolts 44.

The upper ends of plates 40 are secured together by means of a tube 45. This tube is preferably welded to the plates and is anchored to the bottom of plates 40 by means of braces 46-46. Thus it will be seen that members 40, 45 and 46 are rigidly secured together, that the plates are secured to members 10 and that the rear edges of these members are secured to members 42 by means of cushioning washers as illustrated. These cushioning washers act as means to dampen any vibration that might be set up in the frame assembly by the vibration of the fan.

The fan is mounted on the top of tube 45 by means of a bearing sleeve 47 and tube brackets 48. A fan shaft 49 is rotatably mounted in bearing sleeve 47 preferably by roller or ball bearings, the front end of the shaft having secured thereto V-belt sheaves 50.

In Figure 2 I illustrate the sheave as having 6 V-belt grooves for purposes which will hereinafter appear. I mount a fan on the rear end of shaft 49 having blades 51. These blades may be angled as illustrated and turned in the direction indicated by curvilinear arrow so the air is moved rearwardly through the core. By turning the blades at the opposite angle, the circulating air will be drawn through the core. In other words, when the driving belt turns in the direction indicated by arrow, the angle of the fan blades will determine the direction the air travels through the core.

I adjustably mount an idler pulley bracket 52 on member 40 by means of bolts 53 and a series of apertures 54. I rotatably mount shaft 55 in bracket 52 having a V-belt sheave pulley 56. A number of V-belts 57 may be used to drive the fan pulley as illustrated in Figure 1. Sheave 56 will act as a tightener for these belts.

Right and left end members 40 are each provided with apertures 54 thus belt 57 may be made to operatively engage sheaves 50 from either side of the device. The plan illustrated in Figure 1 contemplates the use of driving sheaves on the engine shaft. The device may obviously be positioned on either side of the engine.

Clearly an electric motor may be used for driving the fan, the motor being mounted either on

the unit or separately in a manner which will be understood without further description.

I provide preferably a centrifugal pump 60 having an outlet as at 61 which may be connected to the inlet or inlets of the various cylinder jackets. An inlet connection 62 is provided having preferably a hose connection 63 to outlet 26 of header 21. Thus a convenient yielding connection is made between the header and pump.

Pump 60 is provided with a driving shaft 64 having a bearing 65. This bearing and the pump are mounted on a frame 66 and the frame is adjustably mounted on member 11. Member 11 is provided with a number of spaced slots 67. The bolts for holding member 66 to member 11 are spaced apart a distance equal to the distance between slots 67.

Clearly member 66 may be mounted on the two rear or the two front slots of member 11. Thus the pump may be positioned to accommodate 1 or 2 driving belts for contact with front or rear grooves in sheave 50 and the pump may be moved endwise on member 11 for securing the desired tautness of the belt.

Clearly the pump may be positioned on either end of member 11. Thus it will be understood that member 63 will permit necessary transverse movement of the pump for adjustment of V belts 68. If however, the pump is positioned on the opposite end of member 11 from that shown in Figure 1, an extra length of hose will obviously be necessary.

I provide an inlet connection 69 to header 20 having preferably a pipe connection to a surge tank 70, the connection having a T 71 with an inlet 72. Surge tank 70 is provided with the usual filler cap and an air vent as is customary in devices of the class. Thus the cooling fluid will enter the system as indicated by arrow in Figure 1. Tank 70 will act to maintain a constant supply of fluid to the system and will permit the escape of any vapor that might reach fitting 71.

Thus it will be seen that I have provided means for circulating and cooling the jacket fluid and that I have divided the tubes into groups through which the fluid passes in series as indicated by curvilinear arrows. Clearly partitions 27 and 28 may be dispensed with thus making a one pass core, or other partitions may be supplied and positioned so as to provide either a two or four pass system.

In radiators of the class, especially large units there is a tendency for the tubes to sag. To remedy this difficulty, I provide means for supporting the core at its center as follows:

A plate 75 is provided having a stud 76 which extends through an aperture in channel 77 as indicated in Figures 5 and 8. This channel rests on the upper end of the headers and is provided with downwardly extending flanges 78.

I provide rods 79, two or more of which are secured to one end of plate 75 and the other two or more to the other end of this plate. The rods are spaced and of a size to fill the space between pairs of fins as illustrated and to which they are bonded. Thus nut 80 may be adjusted so as to lift and support the center part of the core and prevent vibration. I may elect to support the core on member 14 either in the same manner by turning the parts end for end or otherwise.

Thus it will be seen that stud 76 will not only support the center of the core but that it will also

prevent vibration which in time cause the tubes to fracture.

I provide a fan shroud 85 which is preferably secured to the headers and to member 77. I provide a wire screen 86 which acts as a shield for the fan blades. This shield is secured to the fan shroud as illustrated and divided into upper and lower portions, the lower portion being cut-away so as not to contact shaft 49 or the hub of the fan.

The screen 86 is divided as at 87, the adjacent edges being bent or turned outwardly and being embraced by a U-shaped strip 88. It will be noted that by removing member 88, the upper and lower portions of member 86 may be removed without disassembling the fan unit.

Clearly many minor detail changes may be made without departing from the spirit and scope of the present invention as recited in the appended claims.

Having thus shown and described my invention, I claim:

1. A device of the class described, comprising an elongated rigid frame, a heat exchange core mounted on the rear end of said frame, said core 25

comprising vertically arranged headers, their bottom ends being flat and resting in direct metal to metal contact on the frame, a multiplicity of closely spaced finned tubes forming operating connections between said headers, a bolt in the bottom of said headers, enlarged openings in said frame through which said bolts extend, yielding means positioned on said bolts and under said openings, means on said bolts 10 adapted to apply pressure on said yielding means to thereby yieldingly hold said header ends and frames together.

2. A device as recited in claim 1 including; narrow plates secured to the front sides of said headers and extending from the frame to near the vertical center of the headers, plates secured at their bottoms to said frame, their rear ends being secured to the front edges of said narrow plates without metallic contact by means of 15 spaced bolts and rubber or the like washers, a cross member secured to near the front upper corners of said last plates and having rotatably mounted thereon intermediate its ends a blower fan.

FRED M. YOUNG.
